US0D1097099S

(12) **United States Design Patent** (10) Patent No.: **US D1,097,099 S**
(45) Date of Patent: ** Oct. 7, 2025

(54) **AIR FRESHENER**

(71) Applicant: **GS27**, Tauxigny (FR)

(72) Inventor: **Alexandre Cognée**, Tauxigny (FR)

(**) Term: **15 Years**

(21) Appl. No.: **29/925,191**

(22) Filed: **Jan. 23, 2024**

(30) **Foreign Application Priority Data**

Jul. 24, 2023 (EM) 015028826-0003

(51) **LOC (15) Cl.** **23-04**

CLAIM

The ornamental design for an air freshener as shown and described.

DESCRIPTION

FIG. 1 is a front and left side perspective view of an air freshener showing my new design.

FIG. 2 is a rear and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
